Mr. Page, Casper, Wyoming

UNITED STATES PATENT OFFICE.

FREDERICK G. KEYES, OF BOSTON, MASSACHUSETTS, ASSIGNOR TO NATIONAL AUTOMATIC REFRIGERATOR COMPANY, A CORPORATION OF NEW JERSEY.

REFRIGERATING MACHINE.

1,277,085.

Specification of Letters Patent. Patented Aug. 27, 1918.

Application filed April 25, 1917. Serial No. 164,354.

To all whom it may concern:

Be it known that I, FREDERICK G. KEYES, a citizen of the United States, residing at Boston, in the county of Suffolk and State of Massachusetts, have invented certain new and useful Improvements in Refrigerating Machines, of which the following is a full, clear, and exact description.

In order that the invention which I shall herein describe as that for which I am seeking protection by Letters Patent may be the more readily understood, I may explain the construction and mode of operation of a refrigerator of now well known character to 15 which the improvement is applicable.

It may therefore be assumed that this apparatus comprises a distilling chamber or receptacle with provision for heating and cooling its interior, and that it is connected 20 with a condenser which is also provided with a cooling coil or similar means for lowering its temperature and with a connection with a refrigerating chamber.

If now, a refrigerating material, which 25 for purposes of the case, may be assumed to be composed of water, ammonium nitrate and ammonia be placed in the distilling chamber, and the latter heated, the ammonia vapor will be driven over to the condenser 30 which is cooled for the purpose of condensing this vapor and delivering it to the refrigerating chamber.

After the ammonia has been all substantially thus driven over, the cooling of the 35 condenser is stopped and the distilling chamber then cooled, whereby the liquid ammonia, owing to its strong affinity for the ammonium nitrate will again volatilize in the refrigerating chamber and pass back 40 into the distilling chamber and enter into the solution therein contained.

For practical reasons it is not desirable that the condensation of the ammonia vapor should take place in the refrigerating chamber, as this involves a lowering of efficiency 45 due to the transfer of heat. It is therefore desirable to insert in the path of the vapor from the distilling to the refrigerating chamber, a condenser which will liquefy

the ammonia and deliver it in liquid form to 50 the refrigerating chamber.

Under ordinary conditions the refrigerating chamber is maintained at a lower temperature than the condenser, so that the normal tendency, were there no intermediate 55 collecting chamber, would be for the liquefaction to take place in the refrigerating chamber rather than in the condenser, but this I have overcome by using as the material for the walls of the refrigerating 60 chamber one having poor heat conductivity, so that although liquefaction may start and may continue to some extent on the walls of the refrigerating chamber, the transfer- 65 ence of the heat thus developed is so delayed, that the temperature of the inner surface may be materially higher than the outer surface of such walls, and so high in fact as to cause the pressure to rise to a point where the condenser will be called upon to con- 70 dense the vapor and deliver it to the refrigerating chamber with its heat of liquefaction abstracted.

This may be accomplished by the use of 75 various materials, but as metals only need be considered for practical reasons, the object should be to use a metal of very poor heat conductivity. Copper, the metal most usually employed, is a very good conductor of heat, and should be discarded. Iron has a 80 conductivity six times worse than copper and may be used to advantage, especially when the walls are made of a thickness that will bring about the necessary delay in heat transfer.

Monel metal has a heat conductivity eighteen times worse than copper, and hence 85 would be the most desirable material for making the walls of the refrigerating chamber.

For purposes of illustration I have annexed hereto a drawing of a refrigerating apparatus containing features which are not claimed in this application, but sufficiently illustrative of the special feature 95 with which I am now concerned. The figure is a diagrammatic illustration of a complete system.

In this apparatus there is shown a household refrigerator, or refrigerating chamber 2, and the object is to supply this chamber with a refrigerant continuously and automatically, this being done in the following manner.

At the right of the diagram is shown a distilling chamber 3, surrounded by an electric heating coil 4, adapted to receive energy 10 at the proper intervals from any suitable source, such as indicated at 1.

In the practical use of this system a composition of ammonium nitrate, water and ammonia is placed in the distilling chamber 15 and by the heating action of the energized coil 4, the volatile constituents of the mixture are driven over through pipe 7, containing a check valve 8, through a condenser 9, and into the refrigerating chamber 2.

20 The condenser is provided with the usual water cooling coils 10, through which, when ammonia is passing, a flow of water is maintained from a source represented by the pipe 11, through a controlling valve 12, and a pipe 13, to an outlet 14.

The condenser 9 is connected with the refrigerating chamber 2, through a pipe 15, carrying at its end any device which will deliver the liquefied ammonia into chamber 30 2, and the condenser 9 is preferably made of copper and so arranged as to secure prompt cooling of the ammonia which streams through it.

In an apparatus of this kind it is possible 35 to distill the ammonia at such a rate as to cause the inner surface of the refrigerating chamber to rise to a temperature considerably higher than the outside surface. Of course, the walls of a refrigerating chamber 40 should be adjusted to thickness to secure as economical operation as possible, and at the same time magnify the effect of the delayed heat transfer as far as practicable. The effect of warming the inner surface of 45 the refrigerating chamber by the heat of condensation is to cause the pressure to rise to a point where ultimately the copper condenser must condense the ammonia, permitting it to flow in liquid form, with its 50 heat of liquefaction abstracted, into the refrigerating chamber.

By this means, in small refrigerators a certain sacrifice in efficiency may be made, but with the result of simplifying to the 55 maximum extent the apparatus used. In practice I have found, when using iron for the refrigerating chamber that this efficiency amounts to about 60%. If a better material, such as Monel metal, were used for the purpose, however, the efficiency would be much higher.

The transfer of ammonia from the distilling chamber to the condenser continues in this way until by the loss of ammonia

the temperature of the chamber 3 rises to 65 about 100° C., at which point of time a circuit is closed through a circuit controller 16 that operates the valve 12 to shut off the water from the condenser and direct its flow through the coils 19 in the distilling 70 chamber.

This operation is effected by any suitable and well known means which forms no part of the present invention and hence need not be described in detail. 75

The valve lever in the movement thus imparted to it, operates the circuit closer 17, and interrupts the circuit through the heating coil 4. The circuit closer is of any proper construction. 80

Under the conditions thus established the strong affinity of the aqueous ammonium nitrate left in the distilling chamber, for the ammonia in the refrigerating chamber causes the latter to pass back from such 85 chamber through pipe 37, to the distilling chamber through a check valve 38. As there is a similar valve 8, in the pipe 7, this is the only path for the ammonia at this time. The ammonia enters the distilling chamber 90 3, when it is absorbed.

As the absorption of the ammonia goes on its level in the refrigerating chamber falls, until it finally reaches a point at which a float 40 operates through any suitable 95 form of mechanism to actuate the circuit closer 18 and through it the water valve to shut off water from the coil 19, in the distilling chamber, and directs it through the condenser coil, and at the same time closes 100 the circuit through the coil 4. This completes the cycle of operations.

My invention is not limited to the form of apparatus above described as it may be used in any kind of refrigerating apparatus 105 where the delayed heat transfer herein set forth will be operative for the same purpose.

What I claim is:—

1. In a refrigerating apparatus of the kind herein described, the combination of 110 a distilling chamber, a refrigerating chamber and an intermediate condenser in which the vapor when driven over from the distilling chamber is intended to be liquefied and delivered in liquid form to the refrigerating chamber, the refrigerating chamber having substantially all of its walls of poor heat conducting material to effect a delayed transfer through them of the heat imparted by the condensation that takes place thereon. 115

2. In a refrigerating apparatus of the kind herein described, the combination of a distilling chamber, a refrigerating chamber and an intermediate condenser connected with the chambers, substantially all of 120 the walls of the refrigerating chamber being of a metal which has poor heat conducting properties whereby the temperature of 125

its inner wall surface raised by the condensation of vapor thereon will increase the pressure within it to a point which will cause the condenser to liquefy the vapor and deliver it in liquid form to said refrigerating chamber.

3. In a refrigerating apparatus of the kind herein described, the combination of

a distilling chamber, a refrigerating chamber and an intermediate condenser connected with both chambers, substantially all of the walls of the refrigerating chamber being composed of Monel metal. 10

In testimony whereof I affix my signature.

FREDERICK G. KEYES.
